UNITED STATES PATENT OFFICE.

FERDINAND J. ZOPPEL, OF CINCINNATI, OHIO.

COMPRESSOR.

1,370,577.

Specification of Letters Patent. Patented Mar. 8, 1921.

Application filed March 31, 1920. Serial No. 370,179.

To all whom it may concern:

Be it known that I, FERDINAND JOSEPH ZOPPEL, a citizen of the Republic of Austria, residing at Cincinnati, in the county of 5 Hamilton and State of Ohio, have invented new and useful Improvements in Compressors, of which the following is a specification.

My invention relates to refrigerating apparatus, its object being to improve the compressor element with a view to produce a simplified and compact unit of novel structure of the highest efficiency and at reduced cost, both of initial construction and maintenance, more perfectly adapted to the needs 10 of hotels, restaurants and other uses of a similar character.

Incidentally any improvements reduce the number of packings to the minimum 20 and eliminate those usually employed with sliding surfaces and subject to the wear incident thereto; carry all movable parts in easily replaceable bushings; and employ a general arrangement and relation of parts 25 giving the fullest and most convenient access, and are contained within a protective casing as a frame and support fully braced against all lateral vibration, insuring minimum of wear and longer life. These improvements taken together tend to increase 30 the capacity in relation to size, thus enlarging the range of usefulness of machines of given size and cost.

My invention in preferred form is as 35 illustrated in the accompanying drawings in which—

Figures 1 and 2 are elevations, taken at right angles one with the other, of the compressor unit;

Fig. 3, an enlarged vertical cross sectional elevation of the apparatus positioned as in Fig. 1;

Fig. 4, a vertical cross section of the cylindrical casing shown on the line E—F of 45 Fig. 1;

Fig. 5, a horizontal cross section of the cylindrical casing in the planes A B of Fig. 3 showing the relation of the separate cored passages;

Fig. 6, a horizontal cross section in the plane C D of Fig. 4.

Referring now to the drawings, my invention is illustrated and embodies in the two-part structure shown in elevation in Figs. 1 and 2 and consists of two integral and independent castings, to-wit: a crank-case 1 with

journal-bearing for a crank-shaft 2 and serving as a base-pedestal for a cylindrical casing 3 super-imposed thereon, having a chambered lateral extension 4 by which it is 60 bolted to the crank-case in a laterally braced and firm connection.

At the top and in the vertical axis of the extension 4 is an enlarged hand-hole closed by a removable cover 5 giving free access 65 from above downward into the suction chamber. The crank-case 1 at the opposite side is likewise provided with an enlarged hand-hole closed by a removable cover 6.

The cylindrical casing 3 is open at the top 70 but provided with a removable cap or hood 7 dished to inclose a cylinder head 9 and is integrally formed with a tubular inner casing 8 axially disposed, utilized as the operative compression cylinder. The cylinder 8 75 is open at the top within the hood 7 and provided with a removable cylinder-head 9 and opens below through the bottom of the casing 3 and is provided there with a removable cylinder-head 10. At the front or right- 80 hand side, as viewed in Figs. 1 and 3 the wall of the casing 3 merges in the walls of the extension 4 (Fig. 5) and the walls of the latter are extended inwardly and merge in the wall of cylinder 8, leaving a vertically 85 elongated opening 11 connecting the inclosure formed by said cylinder 8 and the suction chamber 12 formed by the extension 4. A radially disposed side-wall 13 connects the cylinder 8 at one side with the outer wall of 90 casing 3, forming an inclosed passage 14 which opens above into an interior enlargement 15 of the cylinder 8 and below into a similar enlargement 16, as indicated in Fig. 4. There are thus formed within the inclos- 95 ing wall of the casing 3, three independent chambers, to-wit: an annular water chamber 17 nearly surrounding the inner cylinder 8; an enlarged gas chamber including the interior space inclosed by the cylinder 8, and 100 the suction chamber 12 connected by passage 11; and a compressed gas channel 14 opening into the upper and lower enlargements 15 and 16 respectively. These co-exist without extra parts except the valve-closures of 105 the working cylinder.

A piped supply opening 18 is provided into the extension chamber 4 and a piped exit 19 is provided for the passage 14 as indicated in Figs. 4 and 6. In each of the enlargements 15 and 16 of cylinder 8, is arranged a suction valve cage, valve and

spring, the lower valve seating upwardly and the other downwardly. These being of the common type and operating in the usual manner, require no further description.

5 Within the cylinder 8 is an elongated tubular frame 20 furnished at each end with piston rings to constitute a tight working double piston carrying at the upper end an ordinary plate valve seating downwardly 10 and at the lower end a similar valve seating upwardly. These being also of the common check-valve type, require no further description.

Midway of the length of said tubular piston 15 ton 20 is a cross opening 21 with suitable bushing into which enters the end portion of a gallows-arm 22 extending outward through the opening 11 into the suction chamber 12 of the extension 4. The arm 22 20 is affixed to a cross-head 23 reciprocating in a tubular guide-bushing 24 as shown in Fig. 3, and a similar lower extension into the crank case is connected by a pitman 25 with the crank of the crank-shaft 2 with suitable 25 bushings for the wearing parts.

The reciprocation of the double piston by the crank-shaft and connections described, draws into the cylinder 8, above and below the upper and lower piston elements respectively the gaseous refrigerating element through the respective valves, from the suction chamber 12 through the connecting spaces 11; and, by opposite movement seats the piston valves and forces the gas in compression into and through the chamber 14 30 and outlet 19 into the condenser (not shown). Cooling water enters through pipe orifice 30 into the annular chamber 17 surrounding the cylinder 8, and overflows 35 through the cap space 17 through pipes 27 and 29 (Fig. 4).

The crank-case is also the oil chamber and is provided with a leveling valve 31 at the desired overflow elevation. It will be observed that compression occurs at each stroke 45 in opposite directions and that the gas to be compressed is in relatively large volume immediately contiguous to the suction valves so that a full supply ready for each compression stroke is insured without attenuation 50 by being drawn through exterior passages or parts.

There is thus constituted a compact and self contained compression unit, requiring no 55 packings in connection with moving parts, except for the operating heads of the double piston, and at the outer end of the shaft journal,—these being individually accessible each without disturbing others.

60 In brief also, the pistons and all operat-

ing connections, although entirely within and protected by the general inclosure, can be removed without disturbance of the general structure by the removal merely of the appropriate man-hole cover or covers, and 65 replaced with like convenience.

I claim as my invention and desire to secure by Letters Patent of the United States:

1. A compressor unit for refrigerating apparatus, consisting of a crank-case utilized 70 as a base support and oil chamber, and a casing adapted to be super-imposed thereon, having cored passages and chambers for the compression cylinder; an annular water chamber surrounding same, a gas chamber, 75 and compressed gas-outlet; said crank case and casing being each formed integrally and adapted to be united as a complete unit of structure.

2. In compression apparatus, a crank- 80 case; an operative crank carried therein; a compressor casing adapted to be superimposed upon said crank-case as its base support; a compression cylinder contained within said compressor casing and having 85 access openings outwardly independent of the crank-case; a reciprocating piston in said cylinder and a crank connection between said piston and crank extending through the plane of junction between the casings 90 within their inclosures.

3. In compression apparatus a cylindrical casing having concentrically arranged within the same a smaller cylinder opening outwardly at both ends but otherwise inclosed 95 by said casing, said cylinder having an opening midway into a lateral extension of the casing formed by flaring extensions of the said cylinder wall passing through and merging with the walls of the casing; and a 100 radial wall connecting the walls of the casing and the central cylinder forming a passage connecting at each end with the interior of the cylinder.

4. A double-acting compressor having a 105 reciprocating piston, a crank located within the general inclosure of the apparatus at one side, independent of the cylinder; a pitman operated by said crank through the medium of a sliding cross-head; and a gallows-arm 110 carried by said cross-head and extended laterally into connection with said piston.

In testimony whereof I have hereunto set my hand in presence of two subscribing witnesses.

FERDINAND J. ZOPPEL.
